Werner Block

UNITED STATES PATENT OFFICE.

CHARLES S. RAIZEN, OF BROOKLYN, NEW YORK.

PAPER DOLL.

1,357,421.

Specification of Letters Patent. Patented Nov. 2, 1920.

Application filed November 26, 1919. Serial No. 340,852.

To all whom it may concern:

Be it known that I, CHARLES S. RAIZEN, a citizen of the United States of America, residing at Brooklyn, county of Kings, State 5 of New York, have invented certain new and useful Improvements in Paper Dolls, of which the following is a full, clear, and exact description.

This invention relates to improvements in 10 dolls, and has for an object to provide an inexpensive structure or doll, having movable legs, arms and eyes. My improved doll is made up of flat members, card-board for instance, including body-members, legs and 15 arms, said legs and arms being movably mounted. My improved doll is preferably provided with movable eyes. To accomplish movement on the part of the eyes, legs and arms, I resort to a novel structure, or 20 assemblage of parts, which will herein-after be described.

I will now describe my invention in detail and finally claim the novel features thereof, reference being had to the accompanying 25 drawing, wherein:—

Figure 1 is a face view of one of the body members, illustrating the movable legs, arms and eyes;

Fig. 2 is an enlarged side view thereof, and 30 Fig. 3 is a face view of the doll on a reduced scale.

My improved doll is made up of a plurality of body members 4 and 5 made of such material as flat card-board, wood or metal 35 legs 6, and arms 7 and 8. The doll is preferably reversible, that is to say, each body member 4 and 5 will have printed, pasted, stamped or otherwise applied thereto the picture of an infant; hence, the structure 40 will have the same appearance from both sides. In this event, I employ four arms 7, 7 and 8, 8, one pair for each body member. The arms will preferably be mounted exteriorly of the body members and pivotally 45 secured thereto by eyelets or rivets 9, although they may be secured between the body members 4 and 5. The legs 6 will be integral one with the other, or stamped out of one piece. The leg portion of the doll 50 will be rotatably connected to the body members and between same (see Fig. 2), by an eyelet or rivet 10. The head section of each body member will be provided with eye 55 openings 11 and 12 in line with which eyes 13 will be located. The eyes 13 will be

printed on or otherwise applied to a pivotal arm 14 connected to the head portion of each body member, and between same, by an eyelet or rivet 15. The arm 14 is arranged to swing from side to side, thereby causing the 60 eyes 13 to move from one side of the openings 11 and 12 to the other when the doll is moved along a floor or the like. Movement is imparted to the carrier 14 by the legs 6 when said legs are caused to rotate around 65 the pivot 10. During the rotation of the legs they will contact, in succession, with the adjacent end 16 of the carrier 14, thereby causing said arm to swing sidewise, no matter which direction said leg may rotate. 70 To cause the arms 7, 7 and 8, 8 to move, I connect said arms to said carrier of links 17 and 18. The outer end of each link 17 and 18 engages a pin 19 and each pin 19 passes through an arcuate slot 20 in the body members 4 and 5. Each pin 19, at its outer end, is fastened to an adjacent arm. In other words, the arms 7, 7 will be connected by a pin 19, and the arms 18 will also be connected by a pin 19. During the swinging of 75 the arm 14, the arms will be caused to swing. Adjacent the upper end of arm 14 I secure an elastic member 21 which at its ends is secured to the body members. A pin 22 serves for the securement of the elastic member at 80 its ends. To facilitate the handling of the doll, I provide the body members 4 and 5 with an extension 23 to serve as a handle. When the doll is moved along a floor or the like, the legs being caused to touch the floor, the said legs or leg-carrier 24 will be caused 85 to rotate, which will give to the doll the appearance of walking. During the rotation of the legs the arms and eyes will move. As soon as a leg 6 clears the arm 14, the elastic member will pull said arm to its normal vertical position. The rotation of the legs and action of the elastic member in combination produce a swinging movement upon the 90 part of arm 14.

To enable the doll to stand alone and also to facilitate the maintenance of the doll in a vertical position while being moved along a floor or the like, I provide the doll with standard members 25, which are angularly disposed, thus forming, in combination with the doll, a tripod.

What I claim and desire to secure by Letters Patent is:—

1. In a doll, a plurality of spaced apart 110

flat body-members, a carrier rotatably supported by said body-members, leg members radiating from said carrier, arms 7, 8, pivotally connected to said body members, an 5 arm 14 pivotally connected to said body members, arranged to be moved sidewise by the legs on said leg carrier when said carrier is rotated, an elastic element to restore said carrier to normal position after a leg 10 member has cleared same, and links connecting said arms 7, 8, and said arm 14.

2. In a doll, a plurality of spaced apart flat body members, a carrier rotatably supported by the body members, leg members radiating from said carrier, an arm pivotally connected at one end thereof to said body mem- 15

bers, eyes carried by said arm, one of said body members being provided with eye-openings alining with said eyes, the lower free end of said arm being arranged to contact with the leg members whereby said arm is caused to swing sidewise during the rotation of said carrier, and an elastic member to return said arm to normal position after having been actuated by said legs. 20

Signed at New York city, N. Y., this 25th day of November, 1919.

CHARLES S. RAIZEN.
